UNITED STATES PATENT OFFICE.

JOHN W. MACDOW, OF NEWARK, NEW JERSEY.

DESIGN FOR A LOUD SPEAKER.

Application filed February 15, 1927. Serial No. 20,775. Term of patent 14 years.

To all whom it may concern:

Be it known that I, JOHN W. MACDOW, a citizen of the United States, residing at Newark, in the county of Essex and State of New Jersey, have invented a new, original, and ornamental Design for a Loud Speaker, of which the following is a specification, reference being had to the accompanying drawing, forming part thereof.

The figure is a perspective view of a loud speaker, showing my new design.

I claim:

The ornamental design for a loud speaker, as shown.

JOHN W. MACDOW.
